UNITED STATES PATENT OFFICE.

WILLIAM B. TAYLOR, OF LYNN, MASSACHUSETTS, ASSIGNOR TO GENERAL ELECTRIC COMPANY, A CORPORATION OF NEW YORK.

CONDENSER.

No. 897,500.

Specification of Letters Patent.

Patented Sept. 1, 1908.

Application filed January 5, 1907. Serial No. 350,905.

To all whom it may concern:

Be it known that I, WILLIAM B. TAYLOR, a citizen of the United States, residing at Lynn, in the county of Essex and State of Massachusetts, have invented certain new and useful Improvements in Condensers, of which the following is a specification.

My invention relates to improvements in the construction and arrangement of static electric condensers.

In high voltage condensers difficulty has been experienced in obtaining considerable capacity without making them inconveniently large, in order to guard against breaking down of the dielectric material between the active plates. For this reason also the connection and effective insulation of the leads has been a troublesome matter. By my invention these difficulties are overcome and condensers for high voltage work and having large capacities may readily be built in cheap and compact form.

The various features of novelty constituting my invention will be hereinafter particularly pointed out in the claims; but for a full understanding thereof and of its various objects and advantages, reference is to be had to the following detailed description taken in connection with the accompanying drawings.

In said drawings, Figure 1 is an end elevation of a condenser embodying a preferred form of my invention, the inclosing casing being shown in cross-section and the dielectric being omitted; Fig. 2 is a side elevation of the condenser with the casing shown in cross-section; Fig. 3 shows on an enlarged scale a fragment of one of the condenser units; and Fig. 4 is a side elevation of one of the condenser units on a similar scale.

I prefer to build up condensers of a plurality of similar self-contained units whereby, by assembling more or less of these units, condensers of different sizes may conveniently be produced. Each unit is made up of a plurality of active plates separated from each other and surrounded by solid dielectric material; each unit being therefore a complete condenser.

The condenser shown in the drawing is made up of four of these units 1, 2, 3 and 4. Each unit consists of a pair of electrically-connected separated plates 5 and an interposed plate 6. These plates are preferably formed with rounded corners, as shown in

dotted lines in Fig. 2 and with ears 7 and 8 projecting from one side thereof. The plates are so arranged that the ears 7 and 8, on the plates 5 and 6, respectively, are arranged at opposite sides of the unit. The ears 7 of each unit are bent laterally toward each other so that when they are connected together they serve to hold the plates 5 spaced apart. The ears 7 of the several units are connected together and to a terminal 9 by means of a lead 9^a, and the ears 8 are connected together and to a terminal 10 by means of a lead 10^a. The corners of the plates are cut away as at 11 and 12, respectively, so that the lead connected with each plate or set of plates is far removed from the plate or plates of opposite polarity. The extent to which the plates are cut away of course depends upon the voltage and capacity. By this arrangement the connection of the leads is a simple matter, since they are attached to the plates at points so far removed from the opposing plates that there is little danger of short-circuiting through breaking down of the dielectric between the leads and the plates of opposite polarity. Furthermore, this result is produced without causing the planes of the edges of the plates of opposite polarity to cross except at a single point, a.

The complete structure of one of the units is shown in Figs. 3 and 4. Thus, between the plate 6 and each of the plates 5 there is arranged a solid dielectric material laminated parallel to the plates. This dielectric body 90 may conveniently be made up of a number of sheets 13 of press-board or similar non-conducting material. These sheets, together with other sheets, 14, 14, arranged outside of the plates 5, are cut somewhat 95 larger than the plates, only the ears 7 and 8 projecting beyond them. Interposed between the sheets 13 are a number of dead conducting plates 15 and 16; these plates being cut somewhat larger than the overlapping portions of the active plates so as to reduce to a minimum the edge densities of the active plates and reduce the strain in the non-conducting solid dielectric. It is not necessary that one of these dead conducting 100 plates be placed between each two consecutive non-conducting plates unless the solid dielectric is divided into only a few layers. It is only necessary to provide a few dead 105 conducting plates between adjacent active 110

plates, as, for example, a pair of the plates 15 and another pair of the somewhat larger plates 16. I have found that the best results are obtained by building up the laminated body of a large number of very thin sheets, in which case the dead conducting plates are preferably distributed symmetrically throughout the mass. The dead conducting plates may conveniently be made of 10 tin foil secured to the adjacent non-conducting plates at their upper corners by means of shellac.

The several units are assembled in a frame 17 of wood or other non-conducting material so as to leave spaces between adjacent units, and the frame is then placed in a sheet metal casing 18. The casing may be filled with oil (the surface of which is indicated by the dotted line 18^a in Fig. 1) which, 15 extending between the several units and above and beneath them not only serves as an additional dielectric body but also acts to carry away heat from the surface of the solid dielectric material. The frame may 20 conveniently be made of rectangular boards 19, 19, having a connecting member 20 across the top and a bar 21 joining the lower ends. End members having ribs 22 and 23 are secured to the side members by means 25 of tenons 24 and 25 mortised into the edges of the side members. The condenser units are placed in the frame, one unit between each two consecutive ribs. The lower edges of the units rest upon the member 21 and the 30 units are spaced apart and kept out of contact with each other by means of the ribs 22 and 23. A cleat 25 may be secured in the frame above the several units after they are assembled, in order to hold them against 35 displacement. While the oil serves to cool the solid dielectric, I have found that the heating is largely dependent upon the extent to which the lamination is carried and that over-heating is best avoided by making the 40 laminations of the solid dielectric very thin even when an oil bath is employed.

While I have described in detail only a preferred form of my invention, I do not desire to be limited to this particular form only 45 since, in its broader aspects my invention covers also other modified forms, as will be evident from the definitions in the appended claims. Thus, for example, each unit may consist of any desired number of active 50 plates instead of only three.

What I claim as new and desire to secure by Letters Patent of the United States, is;

1. In a condenser, active plates of opposite polarity and terminal-projections or ears 55 on said plates, each of said plates being cut

away at points adjacent a terminal of opposite polarity.

2. In a condenser, a plurality of rectangular plates of opposite polarity and terminals on said plates, the terminals of opposite polarity being arranged on opposite sides of one of the axes of the plates, and each of the plates having a corner cut away diagonally adjacent a terminal of opposite polarity.

3. In a condenser, a plurality of rectangular plates of opposite polarity and terminals on said plates, the terminals of opposite polarity being arranged on opposite sides of one of the axes of the plates and each of said plates having its corners cut in a rounded fashion and the corner adjacent a terminal of opposite polarity cut away diagonally.

4. A condenser unit consisting of a pair of electrically-connected plates, an interposed plate of opposite polarity, a laminated body 80 of dielectric material containing dead conducting layers arranged between said latter plate and each of the other plates, and terminals on said active plates, each of said active plates being cut away diagonally at 85 points adjacent a terminal of opposite polarity.

5. A condenser unit consisting of a pair of electrically-connected substantially rectangular plates, a similarly shaped interposed 90 plate, laminated bodies of dielectric material separating said plates from each other, said bodies extending beyond the edges of said plates, and terminals consisting of ears on said plates extending beyond the said 95 bodies, each of said plates having its corner cut away diagonally adjacent the ear on the plate of opposite polarity.

6. A condenser consisting of a plurality of active plates of a substantially rectangular 100 shape with a terminal at one corner, an adjacent corner cut diagonally away, the other two corners being cut in a substantially rounded form, alternate plates being assembled with their terminals on opposite 105 sides of one of the axes of the plates, the plates being assembled with the planes of their edges substantially at right-angles to surfaces of the plates, insulated conducting plates placed between the active plates and 110 extending beyond their edges and of greater area as they are spaced further from the active plates, and dielectric material insulating the several plates.

In witness whereof, I have hereunto set 115 my hand this third day of January, 1906.

WILLIAM B. TAYLOR.
